(No Model.)

S. B. GOFF.
AXLE BEARING.

No. 447,608.

Patented Mar. 3, 1891.

UNITED STATES PATENT OFFICE.

SAMUEL B. GOFF, OF CAMDEN, NEW JERSEY.

AXLE-BEARING.

SPECIFICATION forming part of Letters Patent No. 447,608, dated March 3, 1891.

Application filed December 16, 1890. Serial No. 374,906. (No model.)

To all whom it may concern:

Be it known that I, SAMUEL B. GOFF, a citizen of the United States, residing in the city and county of Camden, State of New Jersey, 5 have invented a new and useful Improvement in Journal or Axle Bearings, which improvement is fully set forth in the following specification and accompanying drawings.

My invention consists of a journal or axle 10 bearing constructed as hereinafter described.

Figure 1 represents a sectional view on line $z z$, Fig. 2. Fig. 2 represents a longitudinal section on line $x x$, Fig. 1. Fig. 3 represents a section on line $y y$, Fig. 4. Fig. 4 represents a longitudinal sectional view of a modification of part of the device.

Similar letters of reference indicate corresponding parts in the several figures.

Referring to the drawings, A designates an 20 axle or journal, and B the hub of a wheel mounted thereon, said hub having secured to it the bands C and D. Within the band C, and secured to an angular portion of the axle, or otherwise fastened thereto so as to 25 be stationary, are the spiders E, in which are journaled the anti-frictional rollers F, which are adapted to contact with the inner face of the wall of the band C. A nut G, screwed on the end of the axle within the band C, 30 prevents lateral motion of the spiders E and the anti-frictional rollers F, thus keeping the hub in place on the axle.

Within the band D are the spiders H, stationary on the axle A and carrying the anti-frictional rollers J, which contact with the 35 inner face of the said band D.

K designates a head or annular plate loosely mounted on the axle A and within the band D, adjacent to a spider H, and provided with 40 recesses on its inner and outer circumferential faces adapted to hold the loosely-inserted anti-frictional rollers M and N, respectively, the rollers M bearing against the axle A and the rollers N against the band D. To furnish 45 an additional bearing for the hub, and thereby further distribute the strain on the axle along the same a box P and a supporting arm R are employed. The said box is provided with the anti-frictional rollers S, on 50 which the band D is adapted to bear, and is supported by means of the said arm R, which is firmly secured to the axle A. To lessen

the friction of the hub the box may be lowered by means of the screw-bolt U and nut X, so that the rollers S may be removed from 55 contact with the band D. The screw-bolt U has its head bearing against the under side of the top wall of the box P, so as to sustain the same, and the said box has openings in its side, so as to permit its rise and fall relatively 60 to the band D and axle A. Between the upper wall of the box P and the under side of the arm R ball-bearings V are located in recesses in the said wall of the box and the under side of the arm, respectively, to permit 65 the proper contact of the rollers S with the band D in case of irregularity in their journal-bearings.

In Figs. 3 and 4 are shown views of a modification of the anti-frictional rollers in band 70 D. Instead of a single row of rollers, two rows are employed, one bearing against the axle and one against the band, and instead of journals inserted in spider-bearings ball-bearings W are employed at the ends of the 75 journals, said bearings having play in the inner wall of the band at one end of the roller and in the head K at the other end thereof. In Fig. 3 two of the rollers are shown as removed from the band. The diameter of 80 the opening in the portion of the hub between the bands C and D is such that the hub at said portion does not contact with the axle, said portion forming a bridge, whereby the weight or strain is distributed along the 85 entire portion of the axle between the outer ends of the bands.

Having thus described my invention, what I claim as new, and desire to secure by Letters Patent, is—

1. A hub-band having anti-frictional rollers contacting with the inner periphery thereof and an axle supporting the bearings of said rollers, said bearings being stationary on the axle, substantially as described.

2. A hub with end bands, an axle with bearings in said bands, and anti-frictional rollers movable with said axle and in contact with the bands, said parts being combined substantially as described.

3. The combination of a hub having a band secured to one end, an axle having an end within said hub and band, spiders within said band, secured to said axle, and carrying anti-

frictional rollers contacting with said band, substantially as described.

4. The combination of a hub having a band on one end, a head carrying anti-frictional rollers on both its inner and outer surfaces adapted to bear, respectively, against an inserted axle and the band, and other anti-frictional rollers in said band and bearing against the same, substantially as described.
5. The combination of a hub having a band on one end, an axle with an end in said hub and band, spiders secured to the axle within the band and carrying anti-frictional rollers, and a head in said band carrying sets of rollers on its opposite faces, one set of said rollers being in contact with the band and the other set being in contact with the axle, substantially as described.

6. An axle with an arm secured thereto, a hub with a band on one of its ends bearing 20 on said axle, and a box secured to said arm and having anti-frictional rollers in contact with said band, said parts being combined substantially as described.

7. A hub with a band thereon and an axle 25 with an arm supporting an anti-frictional roller adapted to bear against said band, said parts being combined substantially as described.

SAMUEL B. GOFF.
